ROTATING SPINDLE SEALS FOR VERTICAL MILL
William J. Hill, Holden, Mass., assignor to Morgan Construction Company, Worcester, Mass., a corporation of Massachusetts

Filed May 8, 1963, Ser. No. 278,966

6 Claims. (Cl. 72—249)

This invention relates to vertical roll stands in a continuous rolling mill and more particularly to a means for preventing the contamination of underlying intermediate drive mechanisms with cooling water, mill scale and other foreign matter.

During the rolling operation, the rolls have a tendency to become overheated due to the high temperature of the stock being passed therebetween and the extreme rolling pressure exerted thereon by the rolls. Consequently, cooling water in large quantities is applied directly to the roll surfaces in order to maintain their temperatures within acceptable operating ranges. A second function of the cooling water is to dislodge scale that may have adhered to the surface of the rolls after having been loosened from the stock during the rolling operation. The mixture of cooling water and scale then flows downwardly through the mill stand to a culvert or trough where it is carried away.

This poses no serious problem in the design of horizontal mill stands, since their intermediate drive mechanisms are positioned to one side of the pass line and are not susceptible to contamination by cooling water and mill scale. However, vertical mill stands are commonly driven through intermediate drive mechanisms comprised principally of bevel gears, gear couplings and bearings positioned beneath the mill stand in a pinion and bevel gear housing. Upwardly disposed rotatable drive spindles provide the drive connection between the underlying intermediate drive mechanisms and the vertical rolls rotatably mounted within the roll stand.

When cooling water and mill scale are allowed to contaminate the underlying intermediate drive mechanisms, serious consequences frequently result. The deposit of scale and other foreign matter on the gears and bearing surfaces create excessive wear and result in frequent intervals of down-time during repair and replacement of worn components. In addition, where the cooling water being used is foul or brackish, the corrosion rate of metal components is markedly increased.

Consequently, in present practice, considerable precautions are taken in an attempt to prevent the deposit of water and scale on the intermediate drive mechanisms. Inclined water shed assemblies provided with spindle apertures through which the spindles may extend are usually mounted between the intermediate drive mechanisms and the vertical roll stands in order to direct the deluge of cooling water and mill scale to suitably positioned troughs. Although this method has been successful in dealing with a major portion of the cooling water and scale, considerable difficulty has been experienced in providing an adequate means of preventing water and scale from passing between the outer rotating surfaces of the spindles and the inner edges of the spindle apertures provided in the water sheds. This difficulty has been compounded by the necessity of providing for the various types of movement experienced by the spindles during the normal operation of the mill. More specifically, the spindles must first be allowed to rotate about their longitudinal axes in order to impart rotation to the vertical rolls. Secondly, as the space between the rolls is adjusted during the operation of the mill in order to vary the cross-sectional dimensions of the stock being rolled, the upper extremities of the spindles connected thereto

2

must also be laterally displaced. Finally, some provision must be made for the vertical axial displacement of the spindles during changes in the elevation of the pass line or when a groove in the rolls becomes worn, necessitating the realignment of an alternate groove with the pass line.

Thus it can be seen that a satisfactory seal must not only prevent the passage of water and scale between the rotating outer surfaces of the spindles and the inner edges of the spindle apertures, but in addition must also provide for the various aforementioned spindle movements.

Consequently, an object of the present invention is to provide a water-tight seal between the outer surfaces of the rotating drive spindles and the inner edges of the spindle apertures through which they extend in order to successfully prevent contamination of the underlying intermediate drive mechanisms by cooling water, mill scale and other foreign matter.

Another object of the present invention is to provide a water-tight seal capable of permitting lateral movement of the spindles with respect to the water shed assembly as the space between the vertical rolls is adjusted during the operation of the mill.

A further object of the present invention is to provide a rotating seal assembly slidably mounted on the spindle in order to provide both a water-tight seal between the spindle and the water shed assembly while permitting vertical, axial displacement of the spindle with respect to the seal during corresponding vertical adjustments of the rolls.

Another object of the present invention is to provide a means for removing accumulated mill scale and foreign matter such as grit, contaminated grease and oil from the exposed surfaces of the spindles prior to the slidable axial displacement thereof through the rotating seal.

These and other objects of the present invention will become more apparent as the description proceeds with the aid of the accompanying drawings in which:

FIG. 1 is a sectional view in side elevation taken along line 1—1 of FIG. 3 of a rotating seal assembly according to the present embodiment of the invention shown slidably mounted on the drive spindle and in slidable engagement with the inclined water shed assembly;

FIG. 2 is an enlarged sectional view of a portion of the rotating seal assembly;

FIG. 3 is a view in partial section taken along line 3—3 of FIG. 2;

FIG. 4 is a view in side elevation of the water shed with one spindle and its corresponding rotating seal assembly shown in a raised position and with its spindle aperture closing plates slidably displaced;

FIG. 5 is a plan view in partial section of FIG. 4 taken along line 5—5 of FIG. 4; and

FIG. 6 is a sectional view taken along line 6—6 of FIG. 2.

Referring now to FIG. 1, one of two vertically disposed drive spindles 8 (drive spindle 10 is shown only in FIGS. 4 and 5) is shown extending upwardly from a conventional pinion and bevel gear housing 12 containing intermediate drive mechanisms. The intermediate drive mechanisms are comprised in part of pinion gears 9, spindle couplings 11 and bearings, and are provided in order to transmit power from the main gear drive located on either the drive or work side of the pass line through upwardly disposed spindles 8 and 10 to the vertical rolls mounted within the overlying vertical roll stand.

The housing 12 is partially covered by a conventional inclined water shed assembly generally indicated at 14 and comprised of overlapping roof and canopy portions 16 and 18. Roof portion 16 is bolted to the housing 12 by bolts 20 and overlaps the edges of cross-wise semi-circular discharge troughs 22. The canopy portion 18 is of a peaked configuration and is provided with spindle aper-

tures 22 through which the spindles may extend. The peaked canopy portion 16 overlaps roof portions 18 and is attached to the upper retainer rim 26 of housing 12 by canopy studs 28. The water shed assembly thus described comprises a commonly used means of providing the intermediate drive mechanisms contained within housing 12 with some measure of protection from the descending deluge of cooling water and mill scale during the operation of the mill. Because of the successive overlapping features of canopy 16, roof 18, and troughs 23, water and scale is allowed to flow readily over the inclined stepped surfaces of the shed assembly 14 to the troughs for subsequent removal without leakage between the abutting seams.

Although the above-described apparatus has proved successful in most respects, serious difficulties have been encountered in attempting to provide an adequate seal between the outer rotating surfaces of spindles 8 and 10 and the inner edges 30 of spindle apertures 22. Consequently, water and scale continue to pass therebetween during the operation of the mill, resulting in contamination of the lower intermediate drive mechanisms. As previously mentioned, this difficulty has been compounded by the necessity to simultaneously provide for the aforementioned rotational, axial, and lateral movement of the spindle during the operation of the mill.

The description of the applicant's rotating seal assembly generally indicated in FIG. 1 at 32 will now proceed with particular reference to the enlarged, partial, sectional view of FIG. 2. The rotating seal assembly 32 is comprised principally of a non-rotating sub-assembly slidably mounted with respect to the shed assembly 14 and generally indicated at 34, and a rotatable sub-assembly 36 slidably mounted on the spindle 8 for rotation therewith.

For convenience of description, the non-rotating sub-assembly 34 will first be described. A trunnion housing 38 having a peaked base corresponding to the peak of canopy 18 and provided with longitudinal liners 40 attached to its lower surfaces by screws 42 is slidably mounted on peaked spindle aperture closing plates 44 and 46 in turn supported by canopy 18.

The above-mentioned sliding relationship is provided between trunnion housing 38 and aperture closing plates 44 and 46 in order to enable the seal assembly 32 to move laterally with the spindles during corresponding lateral adjustments of the distance between the vertical rolls rotatably mounted within the overlying vertical roll stand.

The description of the non-rotating sub-assembly 34 will now be temporarily interrupted in order to provide a further description of the structure and function of peaked aperture closing plate 44 in connection with similar aperture closing plates 46 and 48 (shown in FIGS. 4 and 5). It should be mentioned at this time that spindles 8 and 10 are provided with enlarged lower circular sections 50. Sections 50 are in turn provided with spherical gear type coupling components, the outer surface of the female member having splined teeth 11 contained in cooperative engagement with hollow splined pinions 9, thereby providing a conventional means of transmitting power regardless of angular spindle misalignment from the intermediate drive mechanisms contained within housing 12 through the spindles to the vertical rolls rotatably mounted within the vertical roll stands. Consequently, spindle apertures 22 in canopy 18 must be of sufficient diameter to accept enlarged portions 50 during axial insertion or withdrawal of the spindles and coupling components 11 from within the hollow splined pinions 9.

However, without the addition of some means for subsequently restricting the size of aperture 22 following the passage therethrough of lower sections 50, trunnion housings 38 would of necessity have to be of considerable length in order to completely cover spindle apertures 22, yet allow for their abovementioned sliding movement during corresponding lateral displacements of the spindles.

If the trunnion housings were elongated in order to

eliminate the need of aperture closing plates 44 and 46, there would not be space enough to withdraw them through the windows of the upper stand. Furthermore, they would undoubtedly come into contact with upper structural components such as the center section of the scale chute (not shown) during this withdrawal.

For this reason, peaked aperture closing plates 44, 46 and 48 are interposed between canopy 18 and trunnion housings 38 in order to provide a means of subsequently diminishing the lateral dimensions of the spindle apertures corresponding to the axis of lateral displacement of trunnion housings 38. In this manner, the lateral dimensions of trunnion housings 38 can be kept to a minimum without jeopardizing the complete coverage of spindle apertures 22 during their lateral displacements when roll adjustments are made necessitating a corresponding lateral displacement of the spindles.

Referring now to FIGS. 4 and 5, spindle 8 and its rotating seal 32 have been shown in a partially raised position such as would be the case during insertion or withdrawal of the spindle from its hollow splined pinion. In order to provide a better illustration of the function of aperture closing plates 44, 46 and 48, dotted lines 44a, 46a and 48a have been used to indicate the respective positions of aperture closing plates 44, 46 and 48 after they have been laterally displaced in opposite directions to widen spindle aperture 22 to its full dimensions. As can readily be seen from FIG. 5, when the plates are in abutting relationship in their aperture closing position, the enlarged lower spindle section 50 could not be completely withdrawn from the water shed assembly 14. However, by slidably displacing the three aperture closing plates 44, 46 and 48 in opposite directions to positions as indicated in FIGS. 4 and 5 as 44a, 46a and 48a, the original lateral dimensions of spindle aperture 22 are completely regained, making the withdrawal of enlarged section 50 possible. Once the enlarged spindle section 50 has passed through spindle aperture 22 and has been axially inserted within hollow splined pinion 9, spindle aperture closing plates are laterally displaced from their alternate position indicated at 44a, 46a and 48a and returned to their restricting position as indicated at 44, 46 and 48. The rotating seal 32 is then lowered and placed in slidably engagement thereon with its end extremities more than amply covering the now restricted spindle aperture 22.

The procedure for loosening and sliding spindle aperture closing plates 44, 46 and 48 in opposite directions to their alternate positions at 44a, 46a and 48a in preparation for the withdrawal of spindle 8 from spindle aperture 22 will now be described with particular reference to FIG. 2. Spindle aperture closing plates 44, 46 and 48 are positioned in flat relationship on the upper surface of canopy 18. Liner 40 of bronze or some other non-corrosive material is interposed between the upper surface of spindle aperture adjusting plates 44 and 46 and trunnion housing 38 in order to facilitate a sliding relationship therebetween. The outer edges of plates 44 and 46 are in turn clamped within rectangular channel 52 in keeper plate 54 having the intermediate portion of canopy clamp studs 28 extending therethrough. A longitudinal keeper bar 56 having lateral slots 58 positioned therein for receiving studs 28 is positioned on keeper plate 54. The tapered extremity 60 of keeper bar 56 is seated within a similarly shaped longitudinal receiving channel 62 in trunnion housing 38. A longitudinal metal washer 64 is placed intermediate canopy clamp stud nuts 66 and the upper face of keeper bar 56 in order to cover slots 58 and provide a bearing surface for the nuts. By tightening nuts 66, a downward clamping force is exerted through washer 64, keeper bar 56 and keeper plate 54 on aperture adjusting plates 44 and 46. However, it should be carefully noted that when nuts 66 are tightened, a peripheral space remains between the tapered extremity 60 of keeper bar 56 and the inner surfaces of channel 62, thereby allowing trunnion housing 38 to slide on

liners 40 along the upper surfaces of fixed spindle aperture adjusting plate 44 and 46. In this manner, horizontal movement of the seal assembly 32 in conjunction with corresponding angular misalignment of spindle 18 during changes in the space between the vertical rolls is permitted.

A flexible seal 68 is mounted along the outer surface of trunnion housing 38 and held in slidable engagement with the beveled surface 70 of keeper bar 56 by bolts 72, thereby preventing the passage of water and mill scale through the peripheral space between the tapered extremity 60 of gib 56 and the inner surfaces of receiving channel 62.

For ease of description, the combination of keeper plate 54, keeper bar 56, washer 64, canopy clamp studs 28 and canopy clamp stud nuts 66 will hereinafter be referred to as hold-down assembly 67. As can be seen in FIG. 3 and again in FIGS. 4 and 5, the keeper plate of hold-down assembly 67 acts to hold both aperture closing plates 44 and 46. In addition, as can be seen in FIGS. 4 and 5, other identical hold-down assemblies 67a, 69 and 69a are provided in order to securely hold aperture adjusting plates 44, 46 and 48 in place on canopy 18 during the operation of the mill. Consequently, movement of the three aperture adjusting plates requires loosening of the canopy clamp stud nuts of all four hold-down assemblies.

For example, as can be seen in FIGS. 4 and 5, when withdrawal of spindle 8 and seal assembly 32 is necessitated, the canopy clamp stud nuts 66 of hold-down assemblies 67, 67a, 69 and 69a are simply loosened in order to allow for the lateral withdrawal of keeper bars 56 from channels 62. In this manner, nonrotating sub-assembly 34 including trunnion housing 38 is free to be upwardly displaced as the entire rotating seal assembly 32 and spindle 8 are withdrawn from aperture 22. In addition, by loosening stud nuts 66, the downward clamping force exerted on the aperture closing plates 44, 46 and 48 by keeper plates 54 of hold-down assemblies 67, 67a, 69 and 69a is relieved. Consequently, aperture adjusting plates 44, 46 and 48 may be slidably displaced to their alternate positions 44a, 46a and 48a as shown in FIGS. 4 and 5 in order to enlarge spindle aperture 22 and thereby permit the withdrawal therethrough of the enlarged lower spindle extremity 50.

Returning now to FIG. 2 and the description of non-rotating sub-assembly 34, one of two opposed trunnion pin blocks 74 is shown mounted within a receiving aperture cut in the upper circular edge of trunnion housing 38 and held therein by bolts 77 (see FIG. 3). A second trunnion pin block is provided facing trunnion block 74 within an oppositely disposed receiving aperture (see FIG. 1). Although further description of the rotating seal 32 will proceed with reference primarily to the half section shown in FIG. 2, it should be understood as evidenced by FIG. 1 that the description will apply equally to both sides.

A vertical lubricating passageway 78 is drilled downwardly from the receiving aperture containing trunnion pin block 74 through trunnion housing 38 to intersect horizontal lubricating passageway 80. Grease fitting 82, positioned within circular chamber 84, is threaded within passageway 80. Chamber 84 is in turn covered by a threaded removable plug 86 in order to prevent contamination of grease fitting 82 with water and scale.

Each trunnion pin block is further provided with a horizontally disposed circular passageway 88 within which a trunnion pin 90 has been inserted and immobilized by a spot weld as at 92. It should be noted that by spot welding pin 90 within trunnion pin block 74, the lubricating passageway within the pin may be kept in communication with passageway 78 in the trunnion housing.

A circular non-rotating trunnion ring 96 provided with opposed radial apertures 100 containing bushings 98 is 75

pivotaly mounted within the upper circular extremity of trunnion housing 38 by the inwardly disposed enlarged extremity of opposed trunnion pins 90. As can be seen in FIG. 1, in mounting the trunnion ring 96 within the trunnion housing 38, bushings 98 are first inserted within apertures 100. The two welded assemblies comprising pins 90 and blocks 74 are then inserted in bushings 98. The combination of the trunnion ring 96, trunnion pins 90 and trunnion pin blocks 74 is then lowered within the trunnion housing 38 by seating the trunnion pin blocks within the oppositely disposed receiving apertures in the circular upper extremity of the trunnion housing. Bolts 77 are then used to firmly bolt the trunnion pin blocks in place. A flexible seal 102 is then provided between the upper extremity of the trunnion housing 38 and the outer circumference of the trunnion ring 96 in order to provide a hermetic seal, thereby preventing mill scale from passing therebetween. Seal 102 is attached to the upper extremity of trunnion housing 38 by a metal seal retainer 106 fastened by bolts indicated typically at 104, and to the trunnion ring 96 by a wire hoop or snap ring 108.

Thus it can be seen that the trunnion ring 96 is non-rotatable and is pivotaly mounted with respect to the trunnion housing 38 on axially aligned trunnion pins 90. In addition, the trunnion housing 38 is slidably mounted on liners 40 with respect to the fixed upper surfaces of aperture closing plates 44, 46 and 48.

In this manner, as the upper portions of the spindles are laterally displaced during roll adjustments causing them to incline from the vertical, trunnion housing 38 will slide along the aperture adjusting plates and trunnion ring 96 will pivot within trunnion housing 38 to accommodate said inclined position of the spindles.

It should also be mentioned at this time that lubrication of the contact surface between liner 40 and aperture adjusting plate 44 is provided by injecting grease into grease fitting 110 contained within chamber 112 and threaded within passageway 114. Passageway 114 is in turn in communication with aperture 116 in liner 40. In order to prevent contamination of grease fitting 110 during operation of the mill, chamber 112 is covered by a combination plug and welded eye hook 118. The function of the eye hook will be subsequently pointed out.

Having thus described the principal components of the non-rotating sub-assembly 34, attention will now be focused on the components comprising the rotating sub-assembly 36. Spindle bushing 120 is slidably mounted in an axial direction on spindle 8 in order to rotate therewith. Circular woven fiber packing rings 122 are then positioned around the spindle above bushing 120. A washer 124, spring washer 126 and grease ring 128 are then positioned over packing rings 122 followed by top seal ring 130. Top seal ring 130 is provided with apertures 132 through which bolts indicated typically at 134 extend in threaded engagement with bearing sleeve 136 surrounding bushing 120. With this construction, as bolts 134 are tightened, packing rings 122 are compressed between spindle bushing 120 and washer 124 by spring washer 126, thereby providing a sealing means between the surface of the spindle 8 and the rotating sub-assembly 36. In addition, compressed packing rings 122 also serve to promote frictional engagement between the outer surface of spindle 8 and the rotating sub-assembly 36.

A circular recess 137 containing a commercially available seal guard assembly generally indicated at 138 is further provided within top seal ring 130. The seal guard assembly is comprised of a pair of conical bronze sleeves 140 having sharp upper edges held against the outer surface of rotating spindle 8 by a force transmitted through circular resilient seal 142, washer 144 and lock-washers 145 by the tightening of bolts 134. Should a subsequent roll adjustment require the downward axial displacement of the spindle, sleeve 140 will serve to scrape any accumulated mill scale, contaminated grease or other foreign matter clinging to its surface, thereby preventing

their harmful entry into the packing ring chamber and the gear housing.

It should also be noted that an annular passageway 146 is provided between the grease ring 128 and the lower edge of the top seal ring 130. Annular passageway 146 is in communication through passageway 150 with grease fitting 148 in order to provide a means of injecting grease therein. By providing a collar of grease surrounding spindle 8, a further deterrent is created to the passage of water and mill scale between the surface of the spindle and the inner surface of bearing sleeve 136. Thus it can be seen that two seals and a cleaning device are provided between the outer surface of the spindle 18 and the rotating sub-assembly 36.

Having thus described the principal components of the rotating sub-assembly 36, its relationship to the non-rotating sub-assembly 34 will now be discussed. Upper and lower roller bearings 152 and 154 are held in spaced relationship by bearing spacer 156 and positioned intermediate non-rotating trunnion ring 96 and rotating bearing sleeve 136. In this manner, the inner races 152a and 154a rotate while the outer races 152b and 154b remain stationary. Upper roller bearing 152 is further positioned and supported by a suitably disposed recess 153 in trunnion ring 96 and held in position thereon by the lower surface of seal holder 162. A molded lip seal 164 bears against the rotating sleeve 136. The seal is located in seal holder 162 and held in place by retaining ring 168 and bolts indicated typically at 170 threaded into trunnion ring 96. Lower roller bearing inner race 154a is clamped against the lower surface of bearing spacer 156 by a circular curved bearing retainer 172 and bolts indicated typically at 174. A second molded lip seal 176 reinforced with metal strips 178 is positioned between the inner surface of bearing retainer 172 and the lower outer surface of trunnion ring 96 and held in place by a snap ring 180.

Lubrication of upper and lower roller bearings 152 and 154 is provided by grease fitting 82 in communication therewith through passageways 78, 94 and annular passageway 182 between bearing spacer 156 and the inner surface of trunnion ring 96. It should be noted that the lip seals 164 and 176 serve the dual function of preventing the inward seepage of cooling water and mill scale between the rotating and non-rotating sub-assemblies 34 and 36, and the outward flow of grease from the chambers between the rotating and non-rotating components.

In order to further protect the inner components of the seal assembly and to aid in shedding a major portion of the cooling water and mill scale, a circular hood 184 extending over the non-rotating sub-assembly 34 is attached between the bearing sleeve 136 and the top seal ring 130 for rotation therewith.

Having completed the description of both the rotating and non-rotating sub-assemblies, the operation of the rotating seal 32 as a unit will now be reviewed. It should be carefully noted that although the rotating seal assembly was described in terms of two sub-assemblies, in actual practice the seal is an integral unit slipped over the upper extremity of the spindle and axially displaced thereon to its normal operating position.

During the operation of the mill, the rotating sub-assembly 36 rotates freely with spindle 8 as a result of the frictional engagement promoted therebetween by the compressed packing rings 122. Although large amounts of cooling water carrying mill scale and other foreign matter are deposited on the seal assembly, a major portion of the cooling water is deflected by rotating circular hood 184 for subsequent deposit on canopy 18. Because of the collar of grease contained within annular passageway 146 and the compressed woven fiber packing rings 122, no water is allowed to seep between the outer surface of the spindle and the seal assembly. Should some water succeed in splashing under hood 184, hermetic seal 102 and lip seal 164 will prevent its contamination of upper

roller bearing 152 and the pivotal connection of trunnion pin 90 within bushing 100 of trunnion ring 96.

Should horizontal adjustments be required in the space between the vertical rolls, both spindles 8 and 10 and the rotating seals 32 may be laterally displaced without interruption of the watertight seal. The trunnion housing 38 will slide on its liners 40 along the upper surface of aperture adjusting plates 44, 46 and 48 with seal 68 maintaining constant watertight integrity. As the spindles are inclined from the vertical position to accommodate different spaced relationship of the vertical rolls, the trunnion ring 96 will assume a corresponding inclined position by pivoting about the axis of trunnion pins 90.

Finally, should the level of the pass line require vertical adjustment or should the rolls require a pass change, the spindle may be slidably displaced in an axial direction through the seal assembly without again disturbing its watertight integrity. When downwardly displaced, sleeve 140 will scrape any accumulated deposit from the spindle surface, thereby avoiding contamination of the inner seal components. Upward axial displacement of the spindle is also permitted with the keeper bar 56 now acting to keep the seal assembly in place on canopy aperture closing plates 44 and 46.

When removal of the spindle and the seal assembly is necessitated, the spindles are first downwardly displaced to their lowest position. Lifting chains or links 141 are then passed through welded eye hooks 118 and attached at their upper extremities to the lowered vertical roll housing. Stud nuts 66 are then loosened and keeper bars 56 withdrawn from receiving channels 62. After spindle aperture closing plates 44, 46 and 48 have been displaced in opposite directions in order to enlarge spindle apertures 22, the overlying vertical roll housing is raised, carrying with it both the spindle 8 and the spindle assembly 32. After the required maintenance on the underlying drive mechanisms have been performed, the reverse procedure is followed in replacing the spindle and the seal assembly.

It is my intention to cover all changes and modifications of the example of the invention chosen for purposes of disclosure which do not constitute departures from the spirit and scope of the invention.

I claim:

1. For use in a rolling mill, means for preventing the deposit of cooling water and mill scale on the lower intermediate drive mechanisms of vertical roll stands, said means comprising the combination of protective inclined water sheds positioned above said lower intermediate drive mechanisms and below said vertical roll stands, said water sheds provided with spindle apertures through which connecting vertical drive spindles extend from said intermediate drive mechanisms to vertical rolls rotatably mounted within said vertical roll stands, aperture adjusting means for enlarging or contracting the size of said spindle apertures, and rotating seal assemblies slidably mounted on said spindles in slidable engagement with said aperture adjusting means, said seal assemblies positioned intermediate the outer rotating surfaces of said spindles and the inner edges of said spindle apertures, said seal assemblies capable of permitting rotation, axial and lateral movement of said spindles with respect to said water sheds while maintaining a constant watertight seal therebetween.

2. In a continuous rolling mill, for use with drive spindles extending upwardly from underlying intermediate drive mechanisms through spindle apertures in protective inclined water sheds to the vertical rolls contained within the vertical roll stands, a rotating seal assembly positioned intermediate the outer surface of each said drive spindle and the inner edges of said spindle apertures, said rotating seal assembly comprising the combination of rotating and non-rotating sub-assemblies, said non-rotating sub-assembly mounted over said spindle aperture in slidable engagement with said water shed in order to provide the seal assembly with a means of accommodating lateral spindle movements, means for holding said non-rotating sub-as-

sembly in slidable engagement with said water shed and for providing a constant watertight seal therebetween, said non-rotating sub-assembly provided with a passageway therethrough in communication with said spindle aperture, said rotating sub-assembly pivotally mounted within said passageway in order to permit said spindles to incline from a vertical position within said spindle assembly during said lateral spindle movement, said rotating sub-assembly further provided with an inner circular passageway cooperating with said passageway in said non-rotating sub-assembly and said spindle aperture to provide said seal assembly with a means for axially accepting said spindle, said rotating sub-assembly slidably mounted on said spindle for rotation therewith within said nonrotating sub-assembly, bearing means intermediate said rotating and non-rotating sub-assemblies, means for providing a water-tight seal between said rotating sub-assembly and said spindle while permitting sliding axial movement of said spindle therein, and means for providing a water-tight seal between said sub-assemblies while permitting rotation of said rotating sub-assembly within said non-rotating sub-assembly.

3. The combination as set forth in claim 2 wherein said non-rotating sub-assembly is comprised of a trunnion housing having a circular upper extremity and a peaked base, said trunnion housing slidably mounted on said water shed in a position covering said spindle aperture, said trunnion housing having a vertical circular passageway therein in communication with said spindle aperture, oppositely disposed trunnion pin blocks positioned within the upper extremity of said housing, said blocks containing fixed inwardly disposed trunnion pins, means for pivotally mounting said rotating sub-assembly within said passageway comprising a non-rotating circular trunnion ring pivotally mounted on said pins, and means for providing a water-tight seal between said trunnion ring and said trunnion housing.

4. The combination as set forth in claim 2 wherein said rotating sub-assembly is comprised of a circular spindle bushing slidably mounted on said spindle for rotation therewith, a circular bearing sleeve surrounding said bushing and in annular spaced relationship with said spindle, sealing means positioned intermediate said spindle and said bearing sleeve within said annular space for providing a water-tight seal between said spindle and said rotating sub-assembly, and retaining means for containing said sealing means within said annular space.

5. The combination as set forth in claim 4 further characterized by a means for removing accumulated foreign matter from the outer surfaces of said spindle, said means comprising a sharpened circular metal collar positioned on said retaining means and held in slidable engagement

with the outer surface of said spindle in order to scrape said foreign matter from the surface of said spindle prior to its slidable insertion within said rotating sub-assembly.

6. For use in a rolling mill, means for preventing the deposit of cooling water and mill scale on the underlying intermediate drive mechanisms of vertical roll stands, said means comprising the combination of protective inclined water sheds positioned above said underlying intermediate drive mechanisms and below said vertical roll stands, said inclined water sheds provided with spindle apertures through which connecting vertical drive spindles extend from said intermediate drive mechanisms to vertical rolls rotatably mounted within said vertical roll stands, aperture adjusting plates slidably mounted over said spindle apertures on said water sheds in order to provide a means of enlarging or contracting said spindle apertures, and rotating seal assemblies slidably mounted on said vertical spindles, said seal assemblies comprising integrally fabricated rotating and non-rotating sub-assemblies, said non-rotating sub-assemblies mounted over said spindle apertures in slidable engagement with said aperture adjusting plates in order to provide a means of adjusting the position of said seal assemblies during lateral movements of said spindles, means for holding said non-rotating sub-assemblies in slidable engagement with said aperture adjusting plates during vertical axial displacement of said spindles and for providing a constant water-tight seal therebetween, each said non-rotating sub-assemblies provided with an enlarged passageway therethrough in communication with said spindle apertures, said rotating sub-assemblies pivotally mounted within said enlarged passageways in order to compensate for spindle angularity and in turn provided with inner circular passageways in communication with said enlarged passageways and said spindle apertures, said rotating sub-assemblies in sliding axial engagement with said spindles for rotation therewith within said non-rotating sub-assemblies and for lateral displacement therewith with said non-rotating sub-assemblies on said aperture adjusting plates, bearing means intermediate said rotating and non-rotating sub-assemblies, means for providing a water-tight seal between said rotating sub-assemblies and said spindles, and means for providing a water-tight seal between said rotating and non-rotating sub-assemblies.
